UNITED STATES PATENT OFFICE.

MADISON L. GOFF, OF LOS ANGELES, CALIFORNIA.

SIGNAL ARM FOR VEHICLES.

Application filed December 7, 1925. Serial No. 73,940.

My invention relates to signal arms for indicating the proposed action of a vehicle, that is, whether it is going to turn to the left, to the right, or is going to slow down or stop.

5 A signaling system using the human arms for indicating the above has become practically universal and different devices have been produced for taking the place of the human arm and for making the signaling more convenient and certain. It often happens that in extending the human arm the direction or position of the arm is indefinite, or it is in a raised position when it is intended to be straight out, or horizontal. In my improved signaling device I have provided an improved signaling arm which has a permanent position and its operation is a longitudinal extension, and where three arms are used, each has its permanent position and definite direction of 20 extension.

Among the salient objects of my invention are: to provide a signaling arm which is collapsible longitudinally and which is, therefore, also extensible, and which is adapted to 25 be extended by air pressure and to be collapsed by means of a spring; to provide in such an arm an air holding bag or container which is extensible under air pressure and which is extended as the arm structure is extended and which is contracted as the arm structure contracts; to provide a valve for controlling the air under pressure which extends said arm and which valve also permits the escape of said air when it is desired to 30 contract said arm; to provide in connection with a signaling arm means for illuminating said arm from its base and outside thereof, and, in general, to provide a new and improved signaling arm which can be extended and contracted at will and which will occupy a small space when it is in its contracted form.

In order to explain my invention, I have illustrated one practical form or embodiment 45 thereof on the accompanying sheet of drawings, which I will now describe.

Figure 1 is a side elevation of a signaling device embodying my invention, partly in section and in its contracted form; Figure 50 2 is a sectional view of a valve;

Figure 3 is a side elevation of the same, partly in section, in extended form; and Figure 4 is a side elevation of an embodiment 55 of the invention showing three arms, with one extended.

Referring now to the drawings, I will describe in detail the particular embodiment of the invention used for illustration and explanation purposes. A base member, 1, is provided, having two lamp sockets, as 2, 2, to receive the lamps, 3, 3, with a central housing or chamber wall, 4, secured to the sockets, 2, 2, as at 5, by means of an annular flange, 6. A series of telescoping tubular members, designated, 7, 8, 9, 10, 11 and 12, are connected to said central housing, 4, said members being successively smaller, the inner or smaller member, 12, being provided with a cap, 13, adapted when said members are in collapsed or contracted form to cover the outer ends of all of said members, as indicated in Fig. 1, and when said members are extended, as indicated in Fig. 3, said cap is carried out with the inner, or smaller member, 12. Said members are provided with interlocking ends, as at 14, 14, shown in the present form to be of hook-like form, although it is not necessary that they hook together, for I have provided other means to make the structure air tight. An air bag or container, preferably of rubber, is provided, designated 15, and secured at its outer end to the inside of the cap, 13, and at its inner end said rubber bag is fitted over an inner disc wall, 16, and secured by means of an annular wall or partition member, 17, within the housing 4. A coiled spring, 18, is also secured at its outer end within the smaller member 12, and to said cap, 13, and is of substantially uniform diameter within said member 12, while the inner end of said spring is substantially of the form indicated at 18^a, Fig. 1, whereby when said arm is extended, as illustrated in Fig. 3, said spring is also extended, under tension, and when said arm is released, said spring returns to its normal position, contracting the arm, as in Fig. 1.

An air pipe, 19, is connected through the base member, 1, the housing, 4, and through the disc member, 16, for supplying air under pressure to the rubber bag or container, 15, for extending the same. Electric wires, 20, are extended into the base member 1, and to the socket members, 2, 2, for furnishing electric energy to the lamps, 3, 3, for illuminating the same, which lamps illuminate the arm in its extended position, as will be clear from Fig. 3.

I will now describe the valve mechanism shown for controlling the supply of air un-

der pressure to the air bag or container, 15, and as illustrated in Fig. 2. A body, 21, is provided with a chamber, 22, through which is extended a shaft, 23, on which are two eccentric valve members, 24 and 25, said chamber, 22, having an outlet at 26, with a coupling, 27, connecting it with an air pipe, as 19. Said body, 21, has two bores, 28 and 29, in which are secured two valve seat members, 30 and 31, with securing bushings, 32 and 33, with valves, 34 and 35, therein, normally held closed by means of springs, 36 and 37. Couplings, 38 and 39, connect outlet and supply pipes, 40 and 41, respectively, to said body, 21. The valves 34 and 35, are positively opened by the eccentric members, 24 and 25, as the shaft, 23 is turned by means of a handle, 42.

The air under pressure may be taken from 20 a storage tank or any suitable source of supply, which forms no part of the invention proper and is admitted through pipe 41, when valve 35 is opened, said air passing through the chamber 22 in said body, and through 25 pipe, 19, to the signal arm, forcing the same outwardly, as shown in Fig. 3. When the arm is to be contracted, the handle 42, is turned to permit the valve 35 to close, and to open valve 34, which permits the air to escape through pipe 40, which may be extended to any desired and out-of-the-way 30 position. The eccentric members, 24 and 25, operate the valve members, 34 and 35, by direct cam action, and the springs 36 and 37 close them.

In Fig. 4, I have illustrated how the signaling device can be made with three arms instead of one arm, said arms being designated 43, 44 and 45, and being positioned in 40 the three positions for the arm signals, upwardly, outwardly and downwardly. Three lamps, 46, 47 and 48 can be used for illuminating the same, and these can be with colored lamps, red, white and blue, as indicated by 45 the shading of lamps 46 and 48. There would be a valve controlling device for each arm, similar to that shown in Fig. 2, for the arm described in detail. As the invention resides in the construction and operation of a single 50 arm, along the line described, it is not necessary to describe in detail an embodiment of the invention wherein three arms are shown.

I do not limit the invention to the details of construction and arrangement shown for descriptive purposes, except as I may be limited by the hereto appended claims.

I claim:

1. A signal arm adapted to be extended longitudinally and including a series of telescoping tubular members, pneumatic means for intermittently extending the same at will, and lighting means adjacent and on the outside of said signal arm for illuminating the same from the outside.

65 2. A signal arm adapted to be extended lon-

gitudinally and including a series of telescoping tubular members, an extensible air holding member wholly within said telescoping members, and means for directing air under pressure into said extensible air holding member and said arm for extending the same. 70

3. A signal arm adapted to be extended longitudinally and including a series of telescoping tubular members, means for holding air within said members whereby air under pressure can be forced into said arm to extend the same longitudinally, and means for returning the same to contracted position when said air under pressure is released. 75

4. A signal arm adapted to be extended longitudinally and including a series of telescoping tubular members, means whereby air under pressure can be forced into said arm and retained therein to extend the same longitudinally, means for returning the same to contracted position when said air under pressure is released, and means for illuminating said arm. 80

5. A signal arm composed of a series of telescoping tubular members of successively smaller diameters and adapted to be extended longitudinally with the smallest of said members at the outer end thereof when extended, means for holding air under pressure in said members for extending the same, and means 85 for controlling the admission of air under pressure into said arm for extending said members. 90

6. A signal arm composed of a series of telescoping tubular members of successively 100 smaller diameters and adapted to be extended longitudinally with the smallest of said members at the outer end thereof when extended, means for holding air under pressure in said members for extending the same, means for controlling the admission of air under pressure into said arm for extending said members, and means for illuminating said arm. 105

7. A signal arm constructed of a series of 110 tubular members adapted to be extended and contracted longitudinally, an air bag wholly therein adapted to receive air under pressure and to be extended thereby to extend said signal arm, and means for controlling the admission of air under pressure to said air bag and said arm for extending the same longitudinally for signal purposes. 115

8. A signal arm for vehicles including a series of telescoping members adapted to interlock with each other as extended longitudinally, 120 an extensible air holding member therein adapted to be extended with said members, means for forcing air under pressure into said air holding member and said arm for extending the same longitudinally, 125 and a spring adapted to be extended as said telescoping members are extended, said spring being adapted to automatically return said members to contracted form when said air is released. 130

9. A signal arm for vehicles including a series of telescoping members adapted to interlock with each other as extended longitudinally, an extensible air holding member 5 therein adapted to be extended with said members, means for forcing air under pressure into said air holding member and said arm for extending the same longitudinally, a spring therein adapted to be extended as said 10 telescoping members are extended, said spring being adapted to automatically return said members to contracted form when said air is released, and means for illuminating said arm when extended.
- 15 10. A signal arm of the character shown and described and including a series of tubular telescoping members adapted to interlock at their ends when extended, said members being successively smaller in diameter with 20 the smallest member at the outer end when extended, a cap carried by said smallest member and adapted to cover the ends of said members when collapsed, means whereby said telescoping members will hold air under 25 pressure therein for extending the same,
- means for controlling the admission of air under pressure thereto, a spring in said telescoping members adapted to be extended with said members under said air pressure, said spring being adapted to contract said 30 members when said air is released therefrom, and means for illuminating said arm when extended.
11. In a signaling device for vehicles, a base member, a plurality of arms projecting 35 therefrom in different positions and adapted to be extended longitudinally, air holding means in said arms to receive air under pressure to extend the same, means for controlling the admission of air under pressure thereto, a spring adapted to be extended with said arm, said spring being adapted to contract 40 said arm when said air is released, and means for illuminating said arms from the outside, substantially as indicated. 45

Signed at Los Angeles, Los Angeles County, California, this 2nd day of December, 1925.

MADISON L. GOFF.
